US0D1004583S

(12) **United States Design Patent** (10) **Patent No.:** **US D1,004,583 S**
(45) **Date of Patent:** **** Nov. 14, 2023**

(54) **PORTABLE COMPUTER**

(71) Applicant: **Lenovo (Beijing) Co., Ltd.**, Beijing (CN)

(72) Inventors: **Runhao Zhao**, Beijing (CN); **Yuchen Xin**, Beijing (CN)

(73) Assignee: **Lenovo (Beijing) Co., Ltd.**, Beijing (CN)

(**) Term: **15 Years**

(21) Appl. No.: **35/514,546**

(22) Filed: **Apr. 21, 2022**

(80) **Hague Agreement Data**

Int. Filing Date: **Apr. 21, 2022**

Int. Reg. No.: **DM/221340**

Int. Reg. Date: **Apr. 21, 2022**

Int. Reg. Pub. Date: **Jul. 1, 2022**

(30) **Foreign Application Priority Data**

Oct. 22, 2021 (CN) 202130694403.1

(57) **CLAIM**

The ornamental design for a portable computer, as shown and described.

DESCRIPTION

1. Portable computer

1.1 : Front

1.2 : Back

1.3 : Left

1.4 : Right

1.5 : Top

1.6 : Bottom

1.7 : Perspective

1.8 : Front view of first folding state

1.9 : Back view of first folding state

1.10 : Left side view of first folding state

1.11 : Perspective view of first folding state

1.12 : Left side view of second folding state

1.13 : Perspective view of second folding state

The broken lines shown in the drawings illustrate portions of the portable computer and form no part of the claimed
